ABSTRACT OF THE DISCLOSURE

This invention describes the preparation of 3-substituted amino-2-phenylpropiophenones by reacting a substituted desoxybenzoin with formaldehyde and subsequently with an amine, and a method of using the compounds for their central nervous system (CNS) anti-depressant activity.

DESCRIPTION OF THE INVENTION

This invention relates to new compositions of matter. More particularly, it relates to compositions containing as an active component, 3 - substituted amino - 2-phenylpropiophenones and salts thereof with a pharmaceutically acceptable carrier, and methods of administering said compositions.

The physiologically active components of the present compositions may be illustrated by the following formula:

wherein R and R₁ are selected from the group consisting of hydrogen, lower alkyl and cyclo lower alkyl, and X, Y are selected from the group consisting of hydrogen, lower alkyl, lower alkoxy and halo, and the non-toxic salts thereof.

The active components of the compositions of this invention as bases are low melting solids or colorless liquids and the salts such as the hydrochloride salts are white crystalline compounds.

The active components of the compositions of this invention can be prepared by reacting a suitably substituted desoxybenzoin with formaldehyde in a polar solvent such as boiling methanol or ethanol in the presence of a catalytic amount of a base, as for example, piperidine. The resulting substituted methylene desoxybenzoin is added to a liquid amine with or without a solvent such as ether, a lower alkanol or benzene. After removal of the excess amine, the resulting 3-substituted amino-2-phenylpropiophenones can be isolated as oils or low melting solids, or

2

converted into their solid salts. The following equation illustrates the process described above.

The active components of the present invention are physiologically active in warm-blooded animals as antidepressants or stimulants. The dosage of the compounds of this invention will depend on the route of administration, age, weight, and condition of the warm-blooded animal. A total daily dose of from 1 mg. to about 200 mg. per kilogram of body weight given singly or in divided dosage several times daily embraces the effective range of treatment of most conditions for which the compounds are useful. A dosage unit of 10 mg. to 150 mg. is usually sufficient for daily treatment. Parenteral administration generally requires smaller doses than oral administration.

One of the criteria for assessing antidepressant activity is the inhibition of depression of exploratory behavior (in mice) induced by 2 - oxo - 3 - isobutyl-9,10-dimethoxy - 1,2,3,4,6,7 - hexahydro[11,bH]benzo[a]quinolizine (tetrabenazine). Untreated mice, when placed in the center of a horizontal disc, will walk rapidly to the edge of the disc and peer over the edge. A reference depressant agent, such as tetrabenazine, will completely suppress this exploratory behavior. However, exploratory behavior is restored to mice which have been treated with one of the active components of this invention prior to treatment with 2 - oxo - 3-isobutyl-9,10-dimethoxy-1,2,3,4,6,7 - hexahydro[11,bH]benzo[a]quinolizine (tetrabenazine). A clinically used reference antidepressant agent, such as imipramine, 5 - (2-dimethylaminopropyl)-10,11 - dihydro - 5H - dibenz[b,f]azepine hydrochloride, also restores the exploratory behavior of tetrabenazine-treated mice. Tests of this type are described in the following literature: Vernier, V. G. Hanson, H. M. and Stone, C. A., The First Hahnemann Symposium, Ed. Nodine, J. M., Lea and Febig, Philadelphia, Pa., 1962, pp. 683-690. Also, Greenblatt, E. N., and Osterberg, A. C., Toxicology and Applied Pharmacology, 1, 566-578 (1965). Table I shows the lowest dose at which the active components of this invention show this antidepressant activity.

TABLE I.—ACTIVITY OF COMPOUNDS IN PREVENTING TETRABENAZINE-INDUCED DEPRESSION IN MICE

X	Y	R	R ¹	Lowest effective dose, mg./kg. i.p.
H	H	H	H	3.125
H	H	H	CH ₃	0.78

H	p-CH ₃	H	CH ₃	125.0
p-CH ₃	p-CH ₃	H	CH ₃	125.0
Imipramine				1.25

¹ Succinate salt.

Another test which has been used to demonstrate antidepressant activity is the ability to reverse the hypothermia in mice caused by reserpine. (a) Reports by Garattini, S., et al.: J. Pharm. Pharmacol., 14, 509 (1962); (b) Jori A. and Garattini, S. ibid. 17, 480 (1965); (c) Jori A., et al.: ibid., 18, 326 (1966) discuss the observation that agents which are antidepressant also reverse the hypothermia caused by reserpine. Two groups of 10 mice are treated with reserpine (solubilized with propylene glycol and citric acid) at a dose of 5 mg./kg. intraperitoneally. Eighteen hours later, at which time the mean rectal temperature has been reduced 10 to 15° F., one group is treated with one of the components of the present invention at a dose of 10 mg./kg. intraperitoneally and the other group is treated with starch at a dose of 0.2 ml./20 g. body weight. Rectal temperatures are recorded by the use of a tri-R-Electronic thermometer using a 16 gauge probe inserted 3 cm. into the rectum. Two hours after treatment with the active components of the present invention, the hypothermic effects are significantly reversed as shown in the following Table II.

TABLE II.—REVERSAL OF HYPOTHERMIC EFFECTS OF RESERPINE IN MICE

Rectal temp., ° F. Reserpine+Starch (5 mg./kg. I.P.)	Temp., ° F. +3-substituted amino-2-phenylpropiophenone (10 mg./kg. I.P.)	
R	R'	
90.2	H	H
85.2	H	CH ₃
84.8	CH ₃	CH ₃
87.5	H	C ₂ H ₅
84.2	H	n-C ₃ H ₇
92.6	Imipramine (45 mg./kg. I.P.)	
		94.1
		90.1
		91.5
		92.1
		89.1
		96.4

From the above table it is seen that the active components of the present invention are qualitatively similar to the reference compound, imipramine.

We have also found that one of the compounds of the present invention; namely, 3-methylamino-2-phenylpropiophenone hydrochloride, is surprisingly unique in that, in addition to the expected central nervous system stimu-

lant and antidepressant activity, it shows depressant activity, one, by protecting animals against convulsive seizures caused by strychnine and two, by reducing their ability to traverse a horizontal rod in a normal manner. This combination of depressant and stimulant-antidepressant activity indicates a wide range of therapeutic utility in mental disorders of various types, for example, in the management of depressive states, in the treatment of convulsive disorders such as epilepsy, and in the alleviation of anxieties. One measure of depressant activity is the ability to prevent convulsive seizures in warm-blooded animals, e.g., mice, caused by strychnine sulfate. Graded dose levels of the compounds are administered intraperitoneally in a 2% aqueous starch medium to groups of 10 mice at each dose. Strychnine sulfate, dissolved in aqueous saline is administered subcutaneously at doses estimated to cause tonic extensor seizures in 95% of the mice (0.82 milligram per kilogram of body weight). Strychnine is administered 30 minutes after drug treatment. The median effective dose is calculated by the method of Litchfield, J. T. & Wilcoxon, F., "A Simplified Method of Evaluation, Dose-Effect Experiments," Journal of Pharmacology & Experimental Therapeutics, volume 96, pp. 99-113 (1949).

25 The dose of 3-methylamino-2-phenylpropiophenone hydrochloride which protects 50 percent of the mice from convulsive seizures caused by strychnine sulfate is 6 milligrams per kilogram intraperitoneally.

Another measure of depressant activity is the ability to protect against seizures produced by electroshock.

30 Compounds are administered to groups of 10 mice at a dose of 50 mg./kg. Thirty minutes later mice are subjected to maximal electroshock (60 cycle, 50 ma., 0.2 second) via corneal electrodes. If less than 5 mice show

35 protection against tonic extensor seizures, the compound is considered inactive. If 5 or more mice are protected, at least 2 more graded doses are administered to groups of 10 mice each and a median effective dose estimated. The compound 3-amino-2-phenylpropiophenone hydrochloride shows a median effective dose for protection against electroshock seizures of 16.5 mg./kg. The compound 3-ethylamino-2-phenylpropiophenone hydrochloride shows a median effective dose for protection against electroshock seizures of 12.5 mg./kg.

40 A third measure of depressant activity is the loss of ability of warm-blooded animals, such as mice, to traverse a horizontal rod. Groups of 10 mice are treated at a dose of 100 mg./kg. and are tested at 15 and 30 minutes after treatment. If 5 or more mice lose the ability to traverse

45 the rod, groups of 6 mice are then treated with at least two more graded doses, and a median effective dose is estimated. The median effective dose for 3-methylamino-2-phenylpropiophenone hydrochloride is 23 mg./kg.

DETAILED DESCRIPTION

50 The examples which follow describe the preparation of the active components of the present invention and their use in formulations of representative pharmaceutical preparations.

EXAMPLE 1

Preparation of 3-ethylamino-2-phenylpropiophenone hydrochloride

55 Ten grams of methylenedioxobenzoin is added to 20 ml. of liquid ethylamine and the solution is stirred for 1 hour. Ether is added and the solution is evaporated to remove the excess ethylamine. This gives 3-ethylamino-2-phenylpropiophenone as an oil

($\lambda_{\text{max}}^{\text{CHCl}_3}$ 5.94 μ)

60 This oil is dissolved in fresh ether and extracted with 2 N hydrochloric acid. The aqueous acid solution is cooled and basified with sodium hydroxide, and extracted with ether. The dried ethereal extract is treated with hydrogen chloride to give 3-ethylamino-2-phenylpropiophenone

5

hydrochloride, as a white solid. Recrystallization from acetone-ether yields the product, melting point 116.5-119° C., dec.

EXAMPLE 2

Preparation of 3-propylamino-2-phenylpropiophenone hydrochloride

Following the procedure of Example 1 and using n-propylamine in place of ethylamine, the product 3-propylamino-2-phenylpropiophenone is obtained as a colorless oil, which is converted, as in Example 1, to a white crystalline hydrochloride, melting point 154.5-157° C., dec.

EXAMPLE 3

Preparation of 3-cyclopropylamino-2-phenylpropiophenone hydrochloride

When the procedure of Example 1 is followed using cyclopropylamine in place of ethylamine, the product 3-cyclopropylamino-2-phenylpropiophenone is obtained. The product is converted to the hydrochloride which when recrystallized from chloroform-ethyl acetate, is a white solid, melting point 147-150° C., dec.

EXAMPLE 4

Preparation of 4'-chloro-3-methylamino-2-phenylpropiophenone hydrochloride

This compound is prepared by adding 11.6 grams of 2-phenyl-4'-chloroacrylophenone to 15 ml. of liquid methylamine using the procedure described in Example 1. The product, 4'-chloro-3-methylamino-2-phenylpropiophenone, is converted to the hydrochloride, a white solid, melting point 166-168° C., dec.

EXAMPLE 5

Preparation of 3-methylamino-2-(p-methoxyphenyl)propiophenone hydrochloride

When 17 grams of 2-(p-methoxyphenyl)acrylophenone is added to 30 ml. of liquid methylamine following the procedure described in Example 1, the product, 3-methylamino-2-(p-methoxyphenyl)propiophenone is converted to the hydrochloride, a white solid, melting point 148-151° C., dec. (from a mixture of methanol and ether).

EXAMPLE 6

Preparation of 2-(p-chlorophenyl)acrylophenone

A mixture of 46 grams of p-chlorobenzyl phenyl ketone, 480 ml. of methanol, 50 ml. of 37% formaldehyde and 1 ml. of piperidine is stirred and refluxed for 18 hours. The solution is filtered and the filtrate is diluted with 200 ml. of water. The mixture is extracted with methylene chloride and the extracts are washed with dilute sulfuric acid, sodium bicarbonate and water. The methylene chloride extract is then dried and evaporated to give the product, 2-(p-chlorophenyl)acrylophenone as a colorless oil (strong carbonyl absorption at 5.99 μ).

EXAMPLE 7

Preparation of 3-methylamino-2-(p-chlorophenyl)propiophenone hydrochloride

When 40 grams of 2-(p-chlorophenyl)acrylophenone is added to 60 ml. of liquid methylamine following the procedure described in Example 1, the product 3-methylamino-2-(p-chlorophenyl)propiophenone is converted to the hydrochloride, a white solid. After recrystallization from a mixture of chloroform and ethyl acetate, the product melts at 153.5-158.5° C., dec.

EXAMPLE 8

Preparation of 3-methylamino-2-phenylpropiophenone succinate

A solution of 1 gram of 3-methylamino-2-phenylpropiophenone in ethyl alcohol is added to an alcoholic solution of succinic acid. The resultant solution is allowed

6

to stand for several hours. The 3-methylamino-2-phenylpropiophenone succinate slowly separates as a white crystalline solid.

EXAMPLE 9

Preparation of 3-ethylamino-2-phenylpropiophenone fumarate

An alcoholic solution of 3-ethylamino-2-phenylpropiophenone is added to an alcoholic solution of fumaric acid. The resultant solution is cooled, and the 3-ethylamino-2-phenylpropiophenone fumarate separates as a white crystalline solid.

EXAMPLE 10

Preparation of 3-propylamino-2-phenylpropiophenone maleate

An alcoholic solution of 3-propylamino-2-phenylpropiophenone is treated with an alcoholic solution of maleic acid. The resultant solution is cooled, and the 3-propylamino-2-phenylpropiophenone maleate separates as a white crystalline solid.

EXAMPLE 11

Preparation of 2-(p-tolyl)-acrylophenone

2-(p-tolyl)-acetophenone (20.7 g.) is dissolved in methanol (80 ml.). After addition of formaldehyde (37%, 24 ml.), piperidine, (1 ml.), and acetic acid (1 ml.), the solution is refluxed for 4 hours. The cooled solution is diluted with water (100 cc.) and extracted with methylene chloride. The organic layer is rinsed with sulphuric acid (2 N, 50 cc.) and water (100 ml.), dried (magnesium sulfate) and concentrated under reduced pressure to give 2-(p-tolyl)-acrylophenone as a tan oil

(λ =O 6.05 μ)

EXAMPLE 12

Preparation of 3-methylamino-2-(p-tolyl)propiophenone succinate

2-(p-tolyl)-acrylophenone (19 g.) is added to methylamine (50 ml.). After stirring for 1 hour, the excess amine is evaporated under reduced pressure at room temperature. The residual oil is dissolved in ether and the basic portion precipitated with hydrogen chloride gas. After decanting the ether, the hydrochloride is dissolved in water, layered with ether, and converted to the free base by addition of dilute aqueous sodium hydroxide. The aqueous layer is extracted once more with ether, and the combined dried (magnesium sulfate) ethereal solutions evaporated under reduced pressure at room temperature. The residual 3-methylamino-2-(p-tolyl)propiophenone is converted to the succinate and the latter crystallized from methanol (melting point 136-137° C.).

EXAMPLE 13

Preparation of 2-(p-tolyl)-4'-methylacrylophenone

p-Methylbenzyl-p-tolylketone (44.8 g.) is dissolved in methanol (160 cc.). Formaldehyde (37%, 50 ml.), acetic acid (1 ml.), and piperidine (1 ml.) are added and the solution refluxed for 4½ hours. After cooling, water (200 ml.) is added and the solution is extracted with methylene chloride (150 ml.) three times. The organic layer is rinsed with sulphuric acid (2 N, 50 ml.), dilute sodium bicarbonate (50 ml.), and water. The dried (magnesium sulfate) solution is evaporated to give 2-(p-tolyl)-4'-methylacrylophenone as an oil which solidifies upon standing (λ =O=6.05, melting point 46-49.5° C.).

EXAMPLE 14

Preparation of 3-methylamino-2-(p-tolyl)-4'-methylpropiophenone succinate

2-(p-tolyl)-4'-methylacrylophenone (20 g.) is added to liquid methylamine (60 ml.). The solution is stirred for 2 hours, and the excess amine is then evaporated at room

temperature. The residual material is dissolved in ether and the basic portion precipitated with hydrogen chloride gas. After decanting the ether, the hydrochloride is dissolved in water, layered with ether and converted to the free base by addition of dilute aqueous sodium hydroxide. The aqueous layer is extracted once more with ether, and the combined dried (magnesium sulfate) ethereal solutions evaporated under reduced pressure at room temperature. The residual 3-methylamino-2-(p-tolyl)-4'-methylpropiophenone is dissolved in ethanol and converted to the succinate salt by addition of an ethanolic solution of succinic acid. Crystallization from ethanol gives 3-methylamino-2-(p-tolyl)-4'-methylpropiophenone succinate as a white crystalline solid, melting point 130-132° C.

EXAMPLE 15

The present compounds can be dispensed in dosage unit forms such as hard shell capsules or soft shell capsules. A formulation found useful in the preparation of such capsules is as follows:

	Grams
3-methylamino-2-phenylpropiophenone hydrochloride	2.0
Lactose, U.S.P.	300
Magnesium stearate (0.5%)	3.125
	305.125

The formulation is thoroughly mixed and placed as equal quantities in 100 capsules.

EXAMPLE 16

The following example represents a formulation useful in preparing tablets. These tablets can be prepared with sufficient active ingredients for a one third day's use of about 50 mg. Larger tablets can be scored and divided into halves or quantities to be given one to four times a day. Obviously also smaller tablets can be used in multiple doses to obtain the daily amount of active material. The following formulation has been useful.

	Mg.
3-dimethylamino-2-phenylpropiophenone hydrochloride	50
Corn starch	210
Methyl cellulose 400	350
Magnesium stearate 1%	182
Total	792

The above tablet contains 50 mg. of drug which is usually given three to six times a day to obtain about the minimum amount of drug per day for a warm-blooded animal of 60 kg.

EXAMPLE 17

The compounds of the present invention can also be given in the form of tablets containing other formulations as follows:

	Per tablet, grams
3-amino-2-phenylpropiophenone hydrochloride	0.05
Corn starch	0.3
Ethyl cellulose N/10	0.005
Magnesium stearate 1%	0.0016
Total	.3566

The above formulation can be varied by increasing or decreasing the corn starch and by the addition of other ingredients. Also, other disintegrating agents, such as potato starch, may be used in place of corn starch. Other lubricants such as stearic acid, talc and the like can be used. Sweetening agents such as saccharin or sodium cyclohexyl sulfamate and flavoring such as peppermint oil, oil of wintergreen, orange or cherry can be used.

EXAMPLE 18

The compounds of the present invention can be given intramuscularly or subcutaneously in the following formulation:

	Mg.
3 - ethylamino-2-phenylpropiophenone hydrochloride	2,500
Sodium carboxymethylcellulose	10
Sodium chloride	9
10 Tween 80	1
Benzyl alcohol	9
Sterile water to make 50 ml.	

This preparation will contain 50 mg./ml. of the active compound.

EXAMPLE 19

The compounds of the present invention can be given parenterally in the form of parenteral suspensions such as the following:

	Gms.
3-isopropylamino-2-phenylpropiophenone hydrochloride	2.0-5.0
Polysorbitan 80	0.1-0.2
Polyethylene glycol 4000	2.0-5.0
25 Sodium chloride USP	0.5-0.8
Benzyl alcohol	0.9
Pyrogen-free distilled water to make 100.0 ml.	

Each milliliter would contain from 20 mg. to 50 mg. of drug. Obviously, other ingredients can be used in place

30 of the above to prepare desired suspensions. For example, as surfactants in place of polysorbitan 80, ethylene oxide or polyoxypropylene base can be used, and other suspending agents such as carboxymethylcellulose, methylcellulose and gelatin can be used. Other salts than sodium chloride can be used such as sodium phosphates. While benzyl alcohol is a desirable preservative, others can be used such as parabens, chlorobutanol, etc. Also, in place 35 of polyethylene glycol 4000, other vehicles can be used such as polyethylene glycol 400.

40 What is claimed is:

1. The process of producing a therapeutically desirable effect on the central nervous system of warm-blooded animals for the therapeutic treatment of depression which comprises administering internally to warm-blooded animals an antidepressant amount of an amino-2-phenylpropiophenone of the formula:

50 where R is hydrogen and R₁ is selected from the group consisting of hydrogen, lower alkyl and cyclo lower alkyl, and X, Y are selected from the group consisting of hydrogen, lower alkyl, lower alkoxy and chloro, or the non-toxic salts thereof, and a pharmaceutically acceptable carrier therefor.

55 70 75 2. The process according to claim 1, in which the amino-2-phenylpropiophenone is 3-ethylamino-2-phenylpropiophenone.

3. The process according to claim 1, in which the amino-2-phenylpropiophenone is 3-propylamino-2-phenylpropiophenone.

4. The process according to claim 1, in which the amino-2-phenylpropiophenone is 3-methylamino-2-phenylpropiophenone.

5. The process according to claim 1, in which the amino-2-phenylpropiophenone is 3-methylamino-2-(p-methoxyphenyl)-propiophenone.

6. The process according to claim 1, in which the amino-2-phenylpropiophenone is 3-methylamino-2-(p-chlorophenyl)-propiophenone.

7. The process according to claim 1, in which the amino-2-phenylpropiophenone is 3-amino-2-phenylpropiophenone.

8. The process according to claim 1, in which the

amino-2-phenylpropiophenone is 3-isopropyl-2-phenylpropiophenone.

9. The process according to claim 1, in which the amino-2-phenylpropiophenone is 3-methylamino-2-(p-tolyl)propiophenone.
